UNITED STATES PATENT OFFICE.

KNIGHT H. THOMPSON, OF SHELBY, OHIO, ASSIGNOR TO DAVID W. CUMMINS, OF SHELBY, OHIO.

ELECTRIC LAMP FOR VEHICLES.

1,120,001.

Specification of Letters Patent.

Patented Dec. 8, 1914.

Application filed February 16, 1914. Serial No. 816,862.

To all whom it may concern:

Be it known that I, KNIGHT H. THOMPSON, a citizen of the United States of America, residing at Shelby, in the county of Richland and State of Ohio, have invented certain new and useful Improvements in Electric Lamps for Vehicles; and I hereby declare the following to be a full, clear, and exact description of the invention, such as will enable others skilled in the art to which it pertains to make and use the same.

This invention relates to new and useful improvements in electric lamps for vehicles.

The object of this invention is to provide new and improved means for mounting the light bulb in the lamp so that the bulb may be readily removed from the lamp without opening the front of the lamp or disconnecting any of the wires supplying the current to the lamp.

My invention, therefore, consists in the features of construction and combination of parts hereinafter described in the specification, pointed out in the claims and illustrated in the accompanying drawings.

Referring to said drawings, Figure 1 is a central section through a lamp embodying my invention. Fig. 2 is a section on line 2-2, Fig. 1. Fig. 3 is a section on line 3-3, Fig. 1.

Again referring to the drawings, 5 represents the casing or shell of my improved lamp which, as shown in the drawing, is circular in shape and is preferably made of metal so as to be a conductor for electricity. At the front of the casing is mounted a ring 7 which is secured in the casing by means of screws 8. The said ring 7 forms the mounting for the glass or lens 9 which may be held therein in any suitable manner. In the back of the lamp casing is formed a circular opening 10 and on the back of the casing around said opening 10 is formed an interiorly screw-threaded boss 11. A plug 12

45 having an exterior screw thread corresponding to the thread on the boss 11 is screwed into the said boss. This plug 12 is preferably provided with a head 13 in order that it may be readily manipulated. The plug 50 is provided with a chamber 14. In the said chamber 14 in the plug 12 is arranged a lamp receiving socket 15 and the inner end thereof is spaced from the back wall of said chamber. The said socket 15 is provided 55 with a flange 15' which prevents it from be-

ing shoved too far back in the chamber 14. In said socket is formed a centrally arranged screw-threaded bore 16 which extends from end to end thereof and the thread in the said bore is of the standard type for receiving the screw-threaded end of a lamp bulb, shown at 17. Between the lamp socket 15 and the walls of the chamber 14 is arranged an insulating sleeve 18 which completely insulates the lamp socket from the 60 said plug. A contact plate 19 is arranged at the back of the chamber 14 in the plug and is adapted to be engaged by one terminal of the lamp bulb when the bulb is screwed into the lamp socket. A post 20 of 70 any suitable insulating material is secured to the back wall of the lamp casing by means of a bolt 21 and the said bolt extends through the said post and on the end thereof is mounted a terminal strip 22 which is held 75 in place by means of a nut 23 which is insulated from the strip by means of a washer 24 of any suitable insulating material. The end of the said terminal strip abuts against the outer end of the lamp socket 15. A binding post 26 is mounted on the casing and to this binding post is secured one end 27 of the wire which supplies the current, and the other end 28 of the wire is secured to the terminal strip 22.

It will be readily understood that the current will enter the lamp casing from the wire 27, then pass through the plug 12 to one terminal of the lamp bulb, then from the lamp bulb to the lamp socket and 80 through the terminal strip 22 to the wire 28. Now, if it is desired to change the lamp bulb it is only necessary to unscrew the plug 12 from the casing and the old bulb can be readily removed and a new one inserted in 85 the lamp socket after which the plug is screwed back into the lamp casing and all the connections are immediately reestablished.

What I claim is,

1. In an electric lamp for vehicles and the like, the combination of a lamp casing formed of a conducting material, said lamp casing being provided with an opening in the wall thereof, a plug arranged to fit into said opening, said plug being provided with a chamber, a lamp socket arranged in said chamber in said plug, insulating material arranged between the walls of said chamber and said lamp socket, a terminal strip 105

mounted within said lamp casing and insulated therefrom and arranged to contact with said lamp socket, a lamp mounted in the lamp socket and having one of its terminals in electrical contact with said plug and the other terminal in electrical contact with said lamp socket, and means for connecting one terminal of the electric circuit directly to the lamp casing and the other terminal of the circuit directly to said terminal strip.

2. In an electric lamp for vehicles and the like, the combination of a lamp casing formed of a conducting material, said lamp being provided with a screw-threaded opening in one wall thereof, a plug arranged to screw into said opening, said plug having a chamber formed therein, a lamp socket having a screw-threaded bore extending therethrough arranged within said chamber and insulated from the walls of said chamber, a terminal strip mounted within the lamp casing and insulated therefrom and arranged to make contact with the lamp socket, a lamp bulb mounted in the lamp socket and having one of its terminals in electrical contact with said plug, and the other terminal in electrical contact with said lamp socket, and means for connecting one terminal of the electric circuit directly to the lamp casing and the other terminal of the circuit directly to said terminal strip.

3. In an electric lamp for vehicles and the like, the combination of a lamp casing formed of a conducting material, said lamp casing being provided with a screw-threaded opening in the wall thereof, a screw-threaded plug arranged to fit into said opening, said plug being provided with a chamber, a contact plate arranged at the back of said chamber, a lamp socket having a screw-threaded bore extending therethrough arranged within said chamber in said plug and spaced from the rear wall thereof, insulating material arranged between the walls of said chamber and said lamp socket, a terminal strip mounted within said lamp casing and insulated therefrom and arranged to contact with lamp socket, a lamp bulb mounted in the lamp socket and having one of its terminals in electrical contact with the plate at the back of said chamber and the other terminal in electrical contact with said lamp socket, and means for connecting one terminal of an electric circuit directly to said lamp casing and the other terminal of the circuit directly to said terminal strip.

In testimony whereof, I sign the foregoing specification, in the presence of two witnesses.

KNIGHT H. THOMPSON.
